UNITED STATES PATENT OFFICE.

WALTER RUCKSTUHL, OF ORANGE, MASSACHUSETTS, ASSIGNOR TO THE NEW HOME SEWING MACHINE COMPANY, OF ORANGE, MASSACHUSETTS, A CORPORATION OF MASSACHUSETTS.

FEEDING MECHANISM FOR SEWING-MACHINES.

1,182,712.

Specification of Letters Patent.

Patented May 9, 1916.

Application filed November 12, 1914. Serial No. 871,841.

To all whom it may concern:

Be it known that I, WALTER RUCKSTUHL, a citizen of Switzerland, and resident of Orange, in the county of Franklin and State 5 of Massachusetts, have invented certain new and useful Improvements in Feeding Mechanism for Sewing-Machines, of which the following is a specification.

My invention relates to sewing machine 10 feed mechanism of the so-called "four motion" type, and has for its object to provide an improved feed mechanism of this type that will be simple in construction, capable of convenient and accurate adjustment in 15 varying the length of feed stroke, and operative in all of its adjustments with a minimum degree of jar and vibration whereby to assure ease and smoothness in its operation.

20 To this end the invention consists in the novel construction, arrangement and combination of parts hereinafter described and claimed.

Referring now to the accompanying drawings forming part of this specification and 25 in which I have shown only so much of a sewing machine as is necessary to illustrate my invention,—Figure 1 is a bottom plan view of the bed-plate of a sewing machine 30 embodying my invention, with the shuttle mechanism broken away to give a clearer view of the feed device proper. Fig. 2 is a transverse section taken on the line 2—2 of Fig. 1, showing the position of certain of 35 the parts with the feed-adjusting lever set for a maximum length of stitch. Fig. 3 is a corresponding view, showing the position of the parts with the feed-adjusting lever set for the minimum length of stitch, and 40 Fig. 4 is a transverse section taken on the line 4—4 of Fig. 1.

Similar reference characters indicate like 45 parts on the several figures of the drawings.

In the present case I have shown only so much of the frame of the machine as is comprised by the bed-plate thereof, which is indicated by the reference numeral 1.

The feed device, which as before stated 50 is of the so-called "four motion" type, comprises the usual toothed or serrated work-engaging feed-dog 2 mounted on an arm 3 of a frame 4 which is pivotally connected, as by means of bearing screws 5, 5, with a

pair of vertically arranged rock-arms 6, 6, 55 on a rock-shaft 7, which latter is journaled on bearings 8, 8, in a position lengthwise of the bed-plate as shown.

The frame 4 is supported at its free end, that is, the end which carries the feed-dog, 60 by means of an arm 9 of the frame resting upon a cam 10 on the rotary shuttle or looper drive shaft 11, as clearly shown in Figs. 1 and 4. With this arrangement of parts, the cam 10 actuates the frame 4 to impart the 65 required vertical or up-and-down movement to the attached feed-dog 2.

Horizontal or forward-and-backward movement is imparted to the frame 4 and attached feed-dog by a rocking movement 70 of the shaft 7, and this rocking movement is imparted to said shaft 7 from the drive shaft 11 through intermediate connections as follows: A bell-crank lever 12 is mounted on the stationary pivot 13 carried by a 75 hanger 14 at the under side of the bed-plate and is formed with a forked arm 15 embracing a cam 16 on the drive shaft, from which cam the lever receives a rocking movement. The second arm of said bell-crank 80 lever, indicated at 17, is connected through the medium of a pair of toggle links 18, 18, with a horizontally arranged rock arm 19 on the shaft 7, these toggle links being arranged in substantially right-angular relation to each other as shown. A link 20 connects at one end with the toggle links at their joint and at its opposite end connects with an adjustable fulcrum 21 carried by a so-called "feed adjusting lever" 22, which 85 latter is mounted on a stationary pivot 23 with its operating end projecting upwardly through a slot in the bed-plate to a position above the latter where it is provided with a clamping-nut 24 for coacting with 90 an arc-plate 25 to secure the lever with its supported fulcrum 21 in adjusted position. With these described connections from the drive shaft 11 to the rock-shaft 7, rocking 95 movement of the lever 12, as imparted thereto from the actuating cam 16, is communicated to the shaft 7 through the connecting toggle links 18, 18, which are controlled in their movement by the connecting link 20 swinging on the fulcrum support 21, the position of which latter determines the extent of rocking movement 100 imparted to the rock-shaft 7 and thereby the

95

100

105

working stroke of the feed. For instance, with the parts adjusted for a short stroke of the feed, as shown in Fig. 3, in which adjusted position the fulcrum 21 is in substantially a vertical line with the toggle joint, the upper end of the link 20 will move in a substantially horizontal plane and without imparting any substantial movement to the rock-arm 19 and shaft 7 through the connecting toggle link. Upon adjusting the parts for a long stitch, however, as shown in Fig. 2, in which adjusted position the fulcrum 21 has been shifted laterally to bring the link 20 to almost horizontal position, the toggle connecting end of said link will then move in a substantially vertical plane and so effect a maximum movement to the rock-arm 19 and shaft 7, as will be obvious. Any intermediate adjustment of the parts between the maximum adjustments shown will of course effect a corresponding adjustment of feed stroke.

What I claim is:

1. In a sewing machine, the combination with the feed device and means for imparting vertical movement thereto, of means for imparting horizontal movement to said feed device comprising a rock-shaft and a drive-shaft both arranged at the under side of the bed-plate and parallel with each other, the rock-shaft having rock arms one of which is jointed to the feed device and the drive-shaft having an actuating cam, a lever mounted on a stationary pivot below the bed-plate and having operative connection with said cam on the drive-shaft to be rocked thereby, a pair of toggle links connecting said lever with an arm of the rock-shaft,

a feed-adjusting lever, a link connecting at one end with the toggle links at their joint and at its opposite end fulcrumed on said feed-adjusting lever, and means coöperating with the latter to hold same with its said fulcrum in stationary adjusted position, for the purpose set forth. 40 45

2. In a sewing machine, the combination with the feed device and means for imparting vertical movement thereto, of means for imparting horizontal movement to said feed device comprising a rock-shaft and a drive-shaft both arranged at the under side of the bed-plate and parallel with each other, the rock-shaft having rock arms one of which is jointed to the feed device and the drive-shaft having an actuating cam, a bell-crank lever mounted on a stationary pivot below the bed-plate and having a forked arm embracing said cam on the drive shaft to be rocked thereby, a pair of toggle links arranged in substantially right-angled relation and connecting the second arm of said bell-crank lever with an arm of the rock-shaft, a feed-adjusting lever, a link connecting at one end with the toggle links at their joint and at its opposite end fulcrumed on said feed-adjusting lever, and means coöperating with the latter to hold same with its said fulcrum in stationary adjusted position for the purpose set forth. 50 55 60 65

Signed at Orange, in the county of Franklin, and State of Massachusetts, this 6th day of November, A. D. 1914.

WALTER RUCKSTUHL.
